UNITED STATES PATENT OFFICE.

DANIEL W. YOUNG, JR., HENRY B. GRAF, AND CLAYTON O. SHUPERT,
OF MIAMISBURG, OHIO.

FLOOR-COVERING PROTECTOR.

SPECIFICATION forming part of Letters Patent No. 766,210, dated August 2, 1904.

Application filed May 12, 1904. Serial No. 207,514. (No model.)

To all whom it may concern:

Be it known that we, DANIEL W. YOUNG, JR., HENRY B. GRAF, and CLAYTON O. SHUPERT, citizens of the United States, residing at Mi-
5 amisburg, in the county of Montgomery and State of Ohio, have invented certain new and useful Improvements in Floor-Covering Pro-
tectors; and we do declare the following to be a full, clear, and exact description of the in-
10 vention, such as will enable others skilled in the art to which it appertains to make and use the same, reference being had to the accom-
panying drawings, and to the figures of refer-
ence marked thereon, which form a part of this
15 specification.

Our invention relates to new and useful im-
provements in floor-protectors for attachment
to the legs of chairs or various other articles
of furniture.

20 The object of the invention is to provide a device of the above character which, as stated, is attachable to the legs of chairs and serves to prevent any injury to floor-coverings or hard-wood floors due to the tilting or leaning
25 backward of the chairs. In constructing such device we have had an eye single to the requirements of such a device, which are as fol-
lows: First, the base of the device must be flat and sufficiently broad or of a sufficient cir-
30 cumference to provide a substantial flat sur-
face which rests upon the floor and is unaf-
fected by any movements of the chair due to the tilting backward of the occupant or the
35 leaning backward of the occupant of the chair;
secondly, the connection of such a device with the leg of a chair must be such as will enable a free movement of the leg in tilting in any direction without disturbing or affecting the base member.

40 Preceding a detail description of our inven-
tion reference is made to the accompanying
drawings, of which—

Figure 1 is an elevation of our improved
floor-protector, showing the same partially in
45 section and connected with the end of a chair-
leg. Fig. 2 is a detached perspective view of
the base or floor member. Fig. 3 is a view
of a modified construction of that portion of
the device attachable to a square chair-leg.

In a detail description of the invention simi- 50
lar reference characters indicate correspond-
ing parts.

1 designates the base or floor member, the
lower surface 2 of which has a substantial
broad area and is flat throughout with the ex- 55
ception of the annular margin 3, which is
rounded to avoid any sharp edges at the lower
surface. In the middle of the upper side of
said base member there is a semispherical
socket 4, which is inclosed on four opposite 60
sides by lips 5, which extend upwardly above
the center of said socket and inclose a ball 6,
which in connection with said socket forms a
universal joint. The ball 6 is on the lower
end of a leg-socket 7, which receives the end 65
8 of a chair-leg. The lips 5 are of sufficient
length to extend upwardly adjacent to the
neck of the ball in order that the ball may be
caged within the socket and prevented from
removal therefrom during the tilting of the 70
chair. In Fig. 3 the ball 6 is projected from
a leg-socket consisting of two sides which in-
close the forward and back sides of a square
chair-leg 11 and is attachable to said chair-
leg by means of countersunk screws which 75
penetrate the sides.

Having described our invention, we claim—

A floor-covering protector for attachment to
legs of chairs, the same consisting of a base or
floor member having a flat surface of substan- 80
tial area with a semispherical socket in the
upper surface thereof, said socket being sur-
rounded by a series of inclosing lips, a leg
member having a ball projected from the lower
end thereof inclosed within the socket in the 85
base member and maintained therein by said
upwardly-projected lips, as herein shown and
described.

In testimony whereof we affix our signatures
in presence of two witnesses.

DANIEL W. YOUNG, JR.
HENRY B. GRAF.
CLAYTON O. SHUPERT.
